UNITED STATES PATENT OFFICE.

WILLIAM H. MOFFITT, OF LEXINGTON, NORTH CAROLINA.

DESIGN FOR A BUTCHER'S TOOL.

SPECIFICATION forming part of Design No. 35,758, dated February 18, 1902.

Application filed December 14, 1901. Serial No. 35,993. Term of patent 14 years.

To all whom it may concern:

Be it known that I, WILLIAM H. MOFFITT, a citizen of the United States, residing at Lexington, in the county of Davidson and State of North Carolina, have produced a new and original Design for a Butcher's Tool, of which the following is a specification.

This invention relates to a new and original design for a butcher's tool, and the essential features reside in the design as illustrated in the accompanying drawing, which shows a perspective view of the tool.

The design is characterized by a handle 1, with opposite flat sides and convex edges 2, continuing into a terminal 3 of approximately semicircular form. The convex edges 2 forwardly merge into oppositely-projecting angular guards 4, from which extend concave edges 5, and respectively merge into an upwardly-projecting neck 6, with a flat horizontal flanged head 7, provided with an upper corrugated surface 8, and into a downwardly-extending diverged member 9, with a beveled

edge 10, the neck 6 and member 9 being continuous with an intermediate flat body 11. 25 From the front portion of the said body and in alignment with the handle 1 is a blade 12, with intermediate longitudinally-disposed ridges 13, one on each side, and from each ridge faces 14 and 15 slope toward the opposite side edges 16 and 17, the edge 16 being serrated and the edge 17 unbroken. The edges 16 and 17 continue by means of converging bevels 18 at the outer extremity of the blade into a point 19. 30

Having thus described the invention, what is claimed as new is—

The design for a butcher's tool, as herein shown and described.

In testimony whereof I affix my signature 40 in presence of two witnesses.

WILLIAM H. MOFFITT.
